(57) **CLAIM**

I claim the ornamental design for rimless glasses, as shown and described.

DESCRIPTION

FIG. 1 is a front elevational view of the rimless glasses;
FIG. 2 is a rear elevational view of the rimless glasses of FIG. 1;
FIG. 3 is a right-side elevational view of the rimless glasses of FIG. 1;
FIG. 4 is a left-side elevational view of the rimless glasses of FIG. 1;
FIG. 5 is a top plan view of the rimless glasses of FIG. 1;
FIG. 6 is a bottom plan view of the rimless glasses of FIG. 1;
and,
FIG. 7 is a perspective view of the rimless glasses of FIG. 1.
